Primary Examiner — Nicole C Shiflet*Assistant Examiner* — Danielle Nichole Bowly(74) *Attorney, Agent, or Firm* — Bochner PLLC; Serge Krimnus(57) **CLAIM**

The ornamental design for an identification holder, as shown and described.

DESCRIPTION

FIG. 1 is a bottom, front, right side perspective view of the identification holder;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-section view taken along line 8-8 of FIG.

5; and,

FIG. 9 is a top, front, right side exploded perspective view thereof.

The broken line arrows indicate the plane of the cross section view and form no part of the claimed design.

1 Claim, 4 Drawing Sheets(56)
